UNITED STATES PATENT OFFICE.

RALPH NEVIUS PERLEE, OF LONG ISLAND CITY, NEW YORK.

ROSIN-PURIFYING APPARATUS.

961,254.

Specification of Letters Patent. Patented June 14, 1910.

Application filed September 16, 1909. Serial No. 518,055.

To all whom it may concern:

Be it known that I, RALPH N. PERLEE, a citizen of the United States, residing at Long Island City, in the county of Queens 5 and State of New York, have invented certain new and useful Improvements in Rosin-Purifying Apparatus; and I do declare the following to be a full, clear, and exact description of the invention, such as will enable others skilled in the art to which it 10 pertains to make and use the same.

My invention relates to new and improved rosin purifying apparatus and the object of the invention is to separate the rosin from 15 such impurities as sand, stone, splinters of wood, pine needles, etc., the principle depending upon the solubility of the rosin in alcohol and particularly in alcohol at a temperature just below the boiling point 20 thereof.

A still further object of the invention is the provision of novel means for filtering the alcohol diluted rosin and for causing the filtration thereof to take place only when 25 the liquid in the dissolving tank has reached a predetermined level.

With the foregoing and other objects in view, the invention consists of certain novel features of construction, combination and 30 arrangement of parts, as will be more fully described and particularly pointed out in the appended claims.

In the accompanying drawings, Figure 1 is a diagrammatic view of the apparatus; 35 Fig. 2 is a section through the dissolving tank.

Referring more especially to the drawings, 1 represents a still of any suitable character which is arranged above a burner 40 2, by which the contents of the still are heated. Extending from the upper end of the still is a vapor pipe 3, which terminates at its upper end in an acute angle elbow 4 communicating with the liquid pipe 45 5 and with the combined vapor and liquid inlet and outlet 6, leading to the condenser 7. This condenser comprises a plurality of globe shaped receptacles 8 in which the vapor from the still 1 is condensed. Each 50 globe 8 communicates with the succeeding globe by short pipe sections 9.

Mounted immediately below the fluid pipe 5 are two dissolving tanks 10 and 11, the former being connected intermediate 55 the length of the fluid pipe by a valved connection 12 and the latter being connected at

the end of the fluid pipe by a valved connection 13. These tanks comprise a suitable casing 14 which is closed by a cap 15 through which the connections 12 and 13 enter and 60 a hand hole opening 16 through which access may be had to the interior of the tank. The cap is held down upon the casing in any suitable manner, here shown as being secured with flange screws 17. The interior 65 of the casing is divided into separate compartments 18 and 19, separated by a partition 20, composed of any suitable foraminous supporting element and a filtering fabric of cotton batting or the like. 70

The lower end of each tank has leading from it a discharge pipe 21 which communicates with a siphon tube 22 and with a direct discharge tube 23. The siphon tube forms a shunt around the direct discharge tube and around a valve 24 therein which controls the direct discharge tube so that under normal conditions, the filtered liquid will pass around through the siphon tube and back into the still 1 by means of a pipe 80 25. This insures filtration of the solution only when the liquid in the tanks has reached a predetermined level. If it is desired to drain the tank directly, the valve 24 is opened and the liquid in the tank permitted to pass through the pipes 21, 23 and 25, directly to the still 1. The tank 11 is used only when the tank 10 is being refilled. 85

Connected directly to the lower portion of the still 1, is an outlet pipe 26 in which is 90 located a suction pump 27 which draws the liquid from the still 1 and forces it into the upper portion of the still 28. This latter still is heated by a burner 29 and has a condenser coil 30 arranged in the tank 31, 95 which contains cold water, the tank having an inlet at 32 and an outlet at 33.

In operation, the tanks 10 and 11 are filled with rosin in a finely divided state, and alcohol (denatured) is placed within 100 the still 1, sufficient heat is then applied to boil the same and the vapor therefrom arises in the tube 3 to the condenser 7. The vapors enter the condenser through the pipes 6 and the condensed liquid flows out through 105 the same pipe into the liquid tube 5 and through the connection 12 (the connection 13 being closed at this time) and into the dissolving tank 10. The heated alcohol acting upon the rosin in the tank dissolves the same 110 and when the liquid has reached a predetermined level, the pressure thereof causes it

to pass through the filtering fabric and around through the siphon tube 22 into the still 1. This operation is repeated until the rosin has reached a desired concentration, at 5 which time the pump 27 is operated to withdraw the solution from the still 1 when the alcohol in the solution is vaporized and condensed in the spiral 30. The still liquid rosin is withdrawn from the still 28 by 10 means of a spigot 34. When the rosin in the tank 10 has all been dissolved and treated as above described, the connection 12 is closed and the connection 13 opened so that the operation may be practically continuous. During the operation in which the tank 11 is employed, the top 15 of the tank 10 is removed and the sediment resting upon the filtering elements removed.

I have not shown any opening in the still 1 for the admission of a fresh supply of alcohol, but it will be understood that any improved type of opening may be employed which will prevent the escape of the vapor while the burner is in operation.

2 From the foregoing description, taken in connection with the accompanying drawings, the construction and operation of the invention will be readily understood without requiring a more extended explanation.

0 Various changes in the form, proportion and the minor details of construction may be

resorted to without departing from the principle or sacrificing any of the advantages of the invention, as defined in the appended claims.

Having thus described my invention, what I claim is:

1. In a rosin purifying apparatus, the combination with a still, of a condenser, a connection between the still and the condenser, a dissolving tank connected to the condenser, a filtering element arranged in the tank, a siphon connection between the tank and the still, and a direct connection between the tank and the still which shunts 45 the siphon connection.

2. In a rosin purifying apparatus, the combination with a still, of a condenser, a connection between the still and the condenser, a pair of rosin dissolving tanks connected to the condenser to receive the liquid therefrom, means for independently controlling the connection from the tanks to the condenser, and independent siphon connections between the tanks and the still. 50

55 In testimony whereof I have hereunto set my hand in presence of two subscribing witnesses.

RALPH NEVIUS PERLEE.
